UNITED STATES PATENT OFFICE.

MARTIN T. GRAF, OF BUFFALO, NEW YORK, ASSIGNOR OF ONE-HALF TO
JOHN C. BREKER, OF SAME PLACE.

DESIGN FOR A BADGE.

SPECIFICATION forming part of Design No. 30,645, dated May 2, 1899.

Application filed March 21, 1899. Serial No. 709,986. Term of patent 3½ years.

To all whom it may concern:

Be it known that I, MARTIN T. GRAF, a citizen of the United States, residing at Buffalo, in the county of Erie and State of New York, have invented and produced a new and original Design for a Badge or Similar Article, of which the following is a specification, reference being had to the accompanying drawing, forming a part thereof.

10 This design relates to the configuration and ornamentation of a badge, button, or similar article.

The accompanying drawing is a face view of a badge or button embodying my design.

15 The leading feature of my design consists of a background or support of substantially oblong form having rounded upper corners, sharp lower corners, and a straight bar or projection extending upwardly from the upper 20 central portion of the background in resemblance of the outlines of a dust-pan and the representation of an eagle with displayed wings and holding a bunch of arrows in its talons, located upon the flat front side of the 25 background.

Referring to the drawing, A is the flat substantially oblong body forming the background of the badge and having the rounded upper corners, sharp lower corners, and concaved or inwardly-curved lateral edges, as 30 shown in the drawing.

B is the bar which projects upwardly from the upper middle portion of the body A.

C is the representation of an eagle with outspread displayed wings arranged on the flat 35 body portion A, and d is the representation of a bunch of arrows, represented as being held in the talons of the eagle.

What I claim is—

The design for a badge or similar article, 40 substantially as herein shown and described.

Witness my hand this 15th day of March, 1899.

MARTIN T. GRAF.
